UNITED STATES PATENT OFFICE.

BENJAMIN PURNELL, OF BENTON HARBOR, MICHIGAN.

GAME APPARATUS.

1,097,937.

Specification of Letters Patent. Patented May 26, 1914.

Application filed June 9, 1913. Serial No. 772,681.

To all whom it may concern:

Be it known that I, BENJAMIN PURNELL, a citizen of the United States, residing at Benton Harbor, in the county of Berrien 5 and State of Michigan, have invented a new and useful Improvement to be Used in a Game Apparatus, of which the following is a specification.

My invention relates to improvements in 10 a game apparatus, and specifically to that class in which balls are rolled along an alley or table from one end to strike pins pivotally mounted at the other end; and the objects of my improvements are; first, to provide a means for yieldably holding said pivotally mounted pins independently in a vertical position; second, to provide a means for forcing to and holding each of said pins independently in a horizontal position, when 15 said pins are slightly displaced from a vertical position, until acted upon by a resetting device; third, to provide a means whereby images or characters either appear or disappear independently above each of said pins in 20 a quiet uniform manner, upon said pins being slightly displaced from a vertical position, said manner being entirely independent of the force of blows upon said pins; fourth, to provide a means whereby said images or 25 characters may be changed, so that instead of appearing, upon said pins being slightly displaced from the vertical position, they will disappear, or vice versa; fifth, to provide a simple means, operable from the front 30 of the alley or table, for resetting all the pins simultaneously from a horizontal to a vertical position, with a view to economy of manufacture; sixth, to provide a means for elevating balls rolled or thrown along 35 said alley or table, operable in conjunction with said resetting device, to enable their return by gravity to a predetermined height at the front of the alley or table independent of the height of said alley or table, thus enabling the construction of an alley upon the 40 floor and the return of said balls above said alley; and, seventh, to provide a unitary construction of the entire apparatus, operable from the front of the alley or table, 45 such that a single pull on a lever will reset said pins from a horizontal to a vertical position, return images or characters to their

initial position and elevate said balls for their return. I attain these objects by the mechanism illustrated in the accompanying 55 drawings, in which:

Figure 1 is a top view of the pins mounted in a frame over an alley showing the pin resetting and ball returning devices assembled. Fig. 2 is a side view of the ball returning device, sectioned along the line 2—2 in Fig. 1, looking in the direction of the arrow 16 showing the active member of said device in its lowest position. Fig. 3 is a similar view to Fig. 2, showing the active 65 member of said device in its highest position. Fig. 4 is a side view of a pin showing its pivoting and resetting rods. Fig. 5 is a top view of a fragmentary portion of said frame showing one pin in a vertical and another in a horizontal position, and showing 70 two corresponding images with the pin and image actuating device. Figs. 6 and 7 are side views showing respectively the vertical and horizontal position of a pin with an 75 image and their actuating device. Fig. 8 is a front view of a support for an image rod. Figs. 9 and 10 are side and bottom views respectively of an image rod guide.

Similar letters refer to similar parts 80 throughout the several views.

The alley or table "y" having a suitable back stop "f" has supported above it a suitable integral frame, comprising the transverse members "ar" and the longitudinal members "o" upon which pins "a" are pivotally mounted, by means of rods "c" rigidly fastened by the caps "e" to said members "o" of said frame, said rods "c" also serving as pivots for the resetting 85 rods "b" by means of the arms "d" which are rigidly fastened to rods "b" and pivotally fastened to rods "c". Between the points "ac" and the longitudinal members "ae" supported in conjunction with the frame "o" the rods "b" are bent to occupy 90 positions in line with pivoting rods "c", and are rotatably supported by said longitudinal member "ae". Beyond the longitudinal member "ae" the rods "b" are bent so 95 as to form cranks of equal eccentricity which are all connected in similar relative positions to the rod "aa", said rod "aa" being held in its backward position by the 100

spring "z" which supports rods "b" in their highest position out of the path of travel of the pins "a"; except when operated by the rod "q" through the connecting rod "v". This construction enables an economical manufacture of the apparatus, with the frame "o" cast plain throughout, the rods "b" drilled and bent to shape, and the arms "d", which are adapted to be stamped, fastened rigidly to said rods "b", the pivoting rods "c" passed through pins "a" and arms "d", and the pivoting rods "c" rigidly fastened to the frame "o" by the caps "e" which caps are adapted to be stamped.

The ball returning device is so constructed that a forward pull on the rod "q" which goes to a suitable lever at the front of the alley "y" will cause the arm "i" to move about the pivot from the position shown in Fig. 2 to the position shown in Fig. 3, thereby elevating balls thereon and giving said balls potential energy due to their elevation, and kinetic energy due to the forward movement of said arm. The arm "i" is fastened to members "j" by means of the straps "r" pivoted on the fixed straps "t" by the pin "s," one of the straps "r" to which the rod "q" is fastened being braced to the arm "i" by the rod "u". The arm "i" forms a track for balls and is so shaped that when said arm is in its lowest position it is adapted to receive balls from the track formed by the members "h", and when in its highest position is adapted to transfer the balls received to the track formed by members "j" of any predetermined height supported by legs "g".

The arm "i" when in its lowest position, rests upon members "h" with the bumper "w" pressing on the tongue "l", said tongue being fastened at the end farthest from the aforesaid arm, placed between members "h", and having on its free end a lug "m" for the purpose of stopping balls when said arm is in operation, but when not in operation the bumper "m" rests upon said tongue "l", displacing the said lug from the path of balls, thereby providing a free passage of said balls to roll thereon from the track formed by the members "h" which is sufficiently inclined to cause balls to roll thereon, said arm being adapted to receive same ready to be transferred by a pull on the rod "q", to the track formed by members "j". The track makes a turn at the intersection of track-forming members "h" and "ao", and at said turn has suitable wings "k" to keep balls on the track. Said track is inclined so that when balls after traveling along the alley are arrested by backstop "f" and drop upon said track they will travel along the track passing through the opening "ai" until brought to rest by the lug "m" if the arm "i" is in

an elevated position, but if the arm "i" is in its lowest position the balls will continue by gravity until they rest upon said arm where they will remain until the rod "q" is pulled, when said arm will move about the pivot "s" until arrested by the filler "n" coming in contact with the bumper "p".

The height balls are raised depends on the dimensions of the apparatus; and, the horizontal component of the velocity given them by the arm "i" depends on the force with which the rod "q" is pulled. The pull on rod "q" also resets the pins "a" from a horizontal to a vertical position by means of the connecting rod "v" which causes the resetting device to travel about the pivots "c" and when the pull on "q" is relaxed, the resetting device moves out of the path of pins "a" and arm "i" returns to its initial position at rest on members "h" as before described.

Each of the pins "a", of semi-circular cross section is yieldably held in a vertical position, when so placed, by the friction caused by the pressure of a spring "cb" upon its upper surface, said pin being so proportioned and arranged that when it is slightly displaced from the vertical position it will assume a horizontal position on account of pressure of said spring and said spring will move downwardly, and when said pin is reset from the horizontal to the vertical position it will work against said spring, raising it.

The images of characters "ck" are fastened to the rod of square cross-section "cm" by means of the lugs "cl", said rods operating in the holes "cn" in the casting shown in Fig. 8, which castings have openings to admit the strips "ci", said strips having square holes "cq" that serve as a guide to rotate the rods "cm" by means of a twisted portion in the said rods when said rods are moved vertically through said holes. The rods "cm" rest at their lower extremity upon springs "cb" and are twisted so that when said springs move from their lowest to their highest positions, said images will be rotated substantially one quarter of a revolution due to the vertical movement of the square twisted rods "cm" operating in the square holes "cq" so that if said images face the front when said pins are vertical they will be edgewise when the pins are horizontal, in which case if the rods "cm" are lifted out of the square holes "cq" and given a quarter turn and reinserted then said images will be edgewise, viewed from the front when the said pins are vertical and will face the front when said pins are in the horizontal position. Said images are rotated by gravity and consequently are independent of the speed with which the said pins move, thus rendering their operation uniform and quiet.

5 The castings as shown in Fig. 8 are rigidly fastened to the longitudinal members "o" of the aforesaid frame and have ears "cj" projecting across the path of pins "a" to prevent said pins' rotation past the vertical position, and the bumpers "ce" in the transverse members "ar" of the aforesaid frame arrest the rotation of said pins past the horizontal position.

10 The images or characters may be constructed any height above aforesaid frame by lengthening the rods "cm" so that each successive row of images may be higher than the one in front, or any other desired method.

15 While the foregoing description discloses the preferred form of my invention, I do not desire to limit myself to such construction, as I am aware that variations and modifications can be made therein without departing from the spirit or sacrificing the advantages thereof. The right is reserved, therefore, to effect such changes and alterations as may come fairly within the scope of the appended claims.

20 I am aware that prior to this invention a device has been used to reset a plurality of pins from a horizontal to a vertical position in a bowling game apparatus, and that balls have been returned by gravity from the level of their landing at the back of the alley, or by being placed upon a raised track by hand.

25 However, what I claim as new and desire to secure by Letters Patent is:

30 1. A game apparatus comprising an alley or table along which balls may be rolled, a frame mounted above the rearward end of said alley or table said frame being composed of transverse and longitudinal members, a backstop adapted to arrest the progress of said balls so rolled, and a means for returning said balls to the front of said alley or table; in combination with rods 35 clamped rigidly to the under portion of said longitudinal members, each of said rods serving as a pivot for a transverse row of pins placed between said longitudinal frame members and a resetting arm pivoted to each 40 of said rods for resetting the pins.

45 2. A game apparatus comprising an alley or table along which balls may be rolled, a frame mounted above the rear of said alley or table said frame being composed of transverse and longitudinal members, a back stop adapted to arrest the progress of said balls so rolled, means for returning said balls to the front of said alley or table, transverse rods clamped rigidly to the under portion 50 of said frame, pins of semi-circular cross section spaced laterally in successive rows between said longitudinal frame members and pivoted on said transverse rods at points near their upper ends and near their flat side, resetting arms likewise pivoted on said

50 transverse rods, each successive row of pins having its corresponding resetting arm and each resetting rod having a similarly disposed crank connected by a horizontal longitudinal element, the rear end of said connecting element being continually held in its extreme rear position by the tension of a spring except when manually operated from the front of said alley or table by means of a tie rod; in combination with 55 cantaliver springs fastened rigidly to said longitudinal frame members, each spring being adapted to register with the upper portion of one of said pins and by exerting a downward pressure on said upper portion to hold said pin in a vertical position when so placed, but on said pin being displaced from the vertical position the downward pressure of said spring will tend to force said pin to a horizontal position and yieldably hold said pin horizontal.

60 3. In a game apparatus of the character described having pivoted members mounted above an alley or table a means whereby images, characters or other identifying devices supported above said pivoted members are caused to change independently from one position to another upon said pivotally mounted members being slightly displaced from a predetermined position, and to 65 change back to the former position upon said pivotally mounted members being reset to said predetermined position, the said identifying means changing positions in a uniform and silent manner, independent of 70 the force of blows upon said pivoted members.

75 4. In a game apparatus of the class described having pivoted members on each of whose upper surfaces a horizontal portion 80 of a spring presses downwardly, said upper surfaces being so constructed that the said horizontal spring portion moves vertically when said pivoted member is rotated; an image or character removably fastened 85 above each of said pivoted members to a vertical rod which is limited to axial and rotary travel the lower extremity of said vertical rod resting on said horizontal spring portion, said vertical rod being adapted to 90 follow any vertical movement of said horizontal spring portion, said rod having a twisted portion registering with a close fitting guide.

95 5. In a game apparatus of the character described having pivoted members mounted above an alley or table; an image, means whereby said image is supported above each 100 of said pivoted members and is caused to appear (looking from the front of said alley or table) when its corresponding pivoted member is moved from one predetermined position to another predetermined position, and to disappear upon said pivoted member 105 being returned to its original predetermined 110 position.

position, said image being loosely held upon its support whereby it may be lifted therefrom and given a quarter revolution, upon which it will disappear, if, before such 5 quarter revolution it appeared with a corresponding change of pin position, or vice versa.

In testimony whereof, I have hereunto affixed my signature in the presence of the witnesses herein named.

BENJAMIN PURNELL,
